GAUGING DEVICE AND SCREW-DOWN
CONTROL

Howard S. Lamb, Youngstown, Ohio, assignor to
The Cold Metal Process Company, Youngstown,
Ohio, a corporation of Ohio

Application September 26, 1933, Serial No. 690,995

24 Claims. (Cl. 80—56)

My invention relates to metal rolling and, in particular, to an apparatus for gauging the thickness of metal while being rolled and for automatically actuating mechanism for operating screwdowns to insure that the metal will be rolled to a uniform gauge.

Generally speaking, in the rolling of metal to comparatively thin gauges and, particularly, in the rolling of metal in long strips, the metal is elongated without substantial widening. I utilize this fact to determine the percentage of reduction in the gauge of material by comparing the length thereof issuing from a rolling mill in unit time with the length of the material entering the mill in the same time. The ratio of these lengths, obviously, gives accurately the percentage reduction being effected in the mill and, if the initial gauge is known, the desired final gauge may be readily produced.

20 This invention also provides means for automatically actuating the mill screwdowns in response to the indications of the gauging mechanism to insure the production of the desired gauge in the finished material, by tightening the screwdowns if the gauge of the material issuing from the mill is excessive, or by releasing them if the gauge is too small.

Regulators, as known to the prior art, have generally been characterized by the objection that they are subject to hunting. In other words, once a correction is initiated to rectify a departure from a normal condition, the regulator continues to effect such correction until the normal condition is passed through and a reverse abnormal condition created. I avoid this objectionable tendency of prior regulators by rendering my regulator ineffective after a brief period of operation. Instead of applying a continuous correcting force, the apparatus applies a series of brief forces only to the extent required to restore normal conditions.

In accordance with my invention, I provide differential mechanism for comparing the lengths of the material entering and leaving a four-high cold rolling mill. This differential mechanism may take the form of belt driven pulleys or differential gears. Preferably, I utilize a mill of the so-called Steckel type such as that shown in U. S. Patent No. 1,744,018, having winding and unwinding reels for drawing strip back and forth between reducing rolls, and cooling sheaves over which the material passes in its course between reels. The differential mechanism may conveniently be connected to the cooling sheaves, which

are frictionally driven by the material passing thereover at the speed of travel thereof.

A screwdown control mechanism is actuated by the differential mechanism. A friction drive connects a shaft actuated by the mechanism with means for operating screwdown control contacts. A release magnet is provided to free the contact-operating mechanism from the differential shaft after a brief period of screwdown adjustment. A pendulum restores the contact-operating mechanism to neutral and further screwdown operation is prevented unless the differential indicator repeats its operation, demonstrating the necessity for such further adjustment of the screwdowns.

For a complete understanding of the invention, reference is made to the accompanying drawings illustrating a present preferred embodiment of the invention with certain modifications of parts thereof. In the drawings:

Figure 1 is a side elevation of a Steckel mill having the gauging mechanism and screwdown control of my invention incorporated therein;

Figure 2 is a diagrammatic plan view of the apparatus of Figure 1;

Figure 3 is a sectional view along the line III—III of Figure 2;

Figure 4 is a sectional view taken along the line IV—IV of Figure 2 with parts in elevation;

Figure 5 is a sectional view along the line V—V of Figure 4;

Figure 6 is a top plan view of the apparatus shown in Figure 4;

Figure 7 is a partial circuit diagram showing how the contacts operated by the differential mechanism control the screwdown motor;

Figure 8 is a view similar to Figure 1 showing a gauging mechanism of the differential gear type applied to the mill;

Figure 9 is an end view of the structure shown in Figure 8;

Figure 10 is a side elevation of the mill with the differential gear gauger, showing the side of the mill opposite that shown in Figure 8;

Figure 11 is a plan view of the differential gear gauger with the cover removed showing parts in section along the line XI—XI of Figure 10;

Figure 12 is a side elevation of the differential gear gauger mechanism, one wall of its casing being cut away along the section line XII—XII of Figure 11;

Figure 13 is a sectional view along the line XIII—XIII of Figure 11; and

Figure 14 is a sectional view substantially along the line XIV—XIV of Figure 12.

The mill illustrated in Figure 1 comprises a housing 2 having reels 3 and 4 adapted to be driven from a common power source, not shown, and to be employed alternately for reeling and 5 paying out the material. The connection of the reels with the power source is controlled by a lever 5. Material being fed from, say, the reel 3, passes over a cooling sheave 6 and thence past wipers 7 and a guide 8 through work rolls 9. The 10 work rolls are small undriven rolls which are backed by large diameter rolls 10 mounted in anti-friction bearings 11. The issuing material passes over a cooling sheave 12 and thence to the reel 4. The upper backing roll 10 is adjustable 15 vertically. Its bearings are carried in cases 13 slidable in the housing and supported by spring balance mechanism 14. Wedges 15, adjustable laterally by a motor 16, determine the spacing of the work rolls 9 from one another.

20 The cooling sheave 6 is provided with a shaft extension 18 to which is secured a cone pulley 19, and the cooling sheave 12 is provided with a shaft extension 20 to which is secured a cone pulley 21. The shaft extension 18 also carries a 25 loose cone pulley 22 and between the opposed faces 23 and 24 of the pulleys 19 and 22 there is arranged a spider 25 having rollers 26 which engage such faces. The spider 25 also carries pointers 27 cooperating with a graduated arc 28 30 which is held in place by brackets 29 secured to the housing 2 of the mill.

The pulleys 21 and 22 are connected by a crossed belt 30, which belt is preferably a fine but strong cord or thread, such as silk fish line. 35 The pulleys are made very light in weight so as to have a minimum of inertia effect. The belt is kept taut by a belt tightener 31.

The shaft extension 20 also carries a pulley 32 which is loose thereon like the pulley 22 and is connected to the pulley 19 by means of a crossed belt 33. The pulleys 21 and 32 are provided with a spider 25 having a cooperating scale 28, as above described. It is intended that the pointer at one side of the mill shall be used 40 when the mill is being operated in one direction, and that the pointer at the other side shall be used when it is operating in the other direction.

The proper amount of friction between the faces of the cone pulleys and the pulleys 26 on the spiders is obtained by compression spring 34 50 backed by collars 35 on the shaft extensions 18 and 20, the compression springs acting through anti-friction thrust bearings 36 to press the tight and loose pulleys together.

55 Now assume that material is being fed from the reel 3 to the reel 4, and that a certain reduction, say, for example, a 10 percent reduction, is desired. The steps of the cone pulleys are so arranged that the belts may be fitted into different grooves on the pulleys so that the pulley 32 will run faster than the pulley 19 in amounts corresponding to different desired percentages of reduction. In the case just given, if it is a 10 percent reduction in thickness (and no variation 60 in width) there will be a corresponding and definite elongation. Therefore, the cooling sheave 12 will run faster than the cooling sheave 6 in a definite ratio. The belt 33 will therefore be placed in such grooves of the pulleys 19 and 32 65 as will speed up the pulley 32 to give it the same number of revolutions per minute as the pulley 21 makes. However, by reason of the fact that the belt 33 is crossed, the pulleys 21 and 32 will be rotated in opposite directions. If the amount 70 of reduction is exactly that desired, the periph-

eral speed of each of the pulleys 21 and 32 at the point where it engages the rolls 26 will be the same, and therefore the rollers 26 will rotate but their axes will not be moved around the pointer 27 but will stand stationary. If, however, there is even a slight deviation from the desired percentage, the pointer will begin to move in one direction or the other, depending upon whether the reduction is greater or less than that which has been determined upon. Consequently, an 10 adjustment of the pass must be made, as by adjusting the screwdowns.

15 While material is being fed from the reel 3 to the reel 4, the indicator at the right-hand side of the mill will be employed to check the reduction. It will not, however, be necessary to disconnect the indicator at the left-hand side. The pointer 27 of this indicator will simply rotate but will be disregarded. When the mill is driven in the reverse direction the belt 30 will be placed 20 in the proper pulley steps corresponding to the desired percentage of reduction, and the indicator at the left-hand side of the mill will be utilized.

25 The bracket 37 carries a post 38 which provides a bearing for the sleeve on which the pulley 32 is mounted. A differential shaft 39 extends through the bearing 38 and is rotatable in said sleeve. The shaft 39 is driven by the spider 25, as shown in Figure 5, and its outer end is journaled in a bearing in a post 40, also carried by the bracket 37. The post 40 supports a cross bar 41 by means of stud bolts 41a.

30 A friction disc 42 is pinned to the shaft 39. A magnetic disc 43 is rotatably mounted on the shaft 39 and is urged into engagement with the friction disc 42 by a spring 44 extending from the magnetic disc to a thrust bearing 45 supported by the cross bar 41. A pair of electromagnets 46 are mounted on the cross bar 41 on opposite sides of the shaft 39 and, when energized, are adapted to attract the magnetic disc 43 out of engagement with the friction driving disc 42, compressing the spring 44 against the thrust bearing 45. The magnetic disc 43 has a contact-actuating arm 47 with a finger 48 of insulating material. A pendulum arm 49 is also attached to the magnetic disc 43 and has a bob 50 adjustable therewith.

55 An insulating block 51 is secured to the cross bar 41 and is provided with upstanding, fixed contacts 52 and 53 and moving contacts 54. The finger 48 on the arm 47 extends between the contacts 54 and, on rotation of the disc 43, tends to actuate one of the moving contacts 54 into engagement with one or the other of the fixed contacts 52, 53.

60 The manner in which the operation of the mechanism just described controls the motor 16 for actuating the mill screw-downs, will be clear from a study of Figure 7, in which some of the parts already described are shown diagrammatically and designated by the same reference numerals which have previously been employed. As shown in Figure 7, the motor 16 has a control panel 55, including forward and reverse starting relays 56 and 57, as well as other conventional starting contactors and relays, not shown. It will be understood, however, that the contactors forming part of the panel 55, under the control 65 of the relays 56 and 57, control the energization of the motor 16 from a power circuit 58 to effect forward and reverse rotation.

65 With the arrangement shown in Figures 1 and 2, the differential shaft 39 will turn counterclock-

wise if the gauge of the material issuing from the mill is less than that required by the setting of the belt on the shaft. This rotation of the shaft will be immediately communicated to the 5 magnetic disc 43 through the friction disc 42 and angular movement of the arm 47 causes the left hand contact 54 to engage contact 52. As will be apparent from a study of Figure 7, this operation completes a circuit for energizing the relay 10 56 of the control panel 55. The relay 56, when energized, through various other relays and contactors, not shown, as is well known in the art, operates to start the motor 16 to drive the screw-downs so that the top roll is adjusted downward. 15 It will be observed that the magnets 46 are connected in parallel, across the armature of the motor 16. As soon as the motor is energized, therefore, the magnets likewise will be energized to withdraw the magnetic disc 43 from engagement 20 with the friction disc 42. The pendulum bob 58 immediately restores the disc 43 to neutral position and the circuit for the relay 56 is thereby broken and the motor 16 is stopped. The magnets 46 are also de-energized, and the disc 43 re- 25 engages the disc 42. It is obvious that adjustment of the operating time of the relays, contactors and magnets 46 will permit the motor 16 to effect a slight adjustment of the screw-downs before it is stopped. One way of accomplishing 30 this result is to make the magnets 46 of the slow response type by means of a shading coil, thus introducing a certain time delay in the building up of the full flux thereof.

If the initial adjustment of the screw-downs is 35 sufficient to prevent further rotation of the differential shaft 39, no further adjustment occurs. If not, however, the differential shaft again rotates in the same direction and a further adjustment is made, and so on until the proper relation of 40 the speeds of the material entering and leaving the mill is brought about.

If the gauge of the issuing material is too small, obviously, a clockwise rotation of the shaft 39 will result and the right hand contact 54 will 45 engage the contact 53 to energize the relay 57. This relation causes a reverse operation of the motor 16 to raise the screw-downs. This operation, of course, is of the step-by-step type, as above described.

It will be apparent that a duplicate set of contacts and contact-actuating mechanism will be required on the left hand side of the mill, as shown in Figures 1 and 2, so that proper screw-down operation will be obtained for both directions of movement of the material. The contacts may be connected in parallel to the relays of the panel 55 and alternately inserted and removed from the circuit by a simple switching operation by obvious means, not shown. The retracting magnets of the device not in use may be continuously energized during the reversing period by any suitable switch mechanism, to free the contact operating disc from the differential shaft.

A preferred form of the gauging mechanism 5 per se, which is also adapted for operating the screwdown controlling contacts, is shown in Figures 8 through 14. The differential mechanism is mounted in a case 60 secured to one side of the mill housing on a bracket 61. This form of the 10 invention is similar in principle to that already described but differs therefrom in that the differential mechanism is made up of gears instead of pulleys and belts. The gear form of the device presents certain advantages in that it avoids any slippage or change in tension of the belts. A

positive drive is thus assured which renders the gear device more accurate than the pulley and belt mechanism.

The mill to which the differential gear mechanism 60 is applied, is similar in general to that shown in Figure 1, and corresponding parts are indicated by the same reference numerals. I provide, however, for utilizing the same gauging mechanism regardless of the direction of movement of the material. Instead of duplicating the 10 gauger mechanism, I reverse the drives of the two ends thereof. A differential gear reversing lever 62 is journaled in bearings on the bottom of the bracket 61. The end of the lever is connected by a link 63 to a crank 63a on a shaft 64 extending across the mill and journaled in the housings. A crank 65 for operating the rod 64 is connected to the main reversing lever 5 by a link 66. When the mill is reversed by operation of the lever 5, therefore, the gauging mechanism is automatically actuated so that it is operative for the reverse movement of the material.

As in the pulley and belt mechanism, it is necessary to compare the lengths of the material entering and issuing from the mill. In the preferred form of the apparatus, I provide helical gears 67 mounted on extensions of the shafts of the cooling drums. Gear cases 68 mounted on the mill housings provide bearings for shafts 69 having helical gears 70 thereon meshing with the 25 gears 67. The shafts 69 at opposite ends of the mill are connected to shafts 71 and 72 journaled in suitable bearings 73 on the bottom of the case 60, by means of universal joints and connecting shafts 74.

Referring now particularly to Figures 11 through 14 for a disclosure of the details of the differential gear gauger, it will be seen that the shafts 71 and 72 are provided with gears 75 and 75a respectively. Each of these gears is provided 40 with a clutch member adapted to cooperate alternately with one of two similar members on the ends of a shaft 76 journaled in movable bearings 77. The shaft 76 is provided with a gear 78 for a purpose which will appear later.

Gears 79 and 80, meshing with gears 75 and 75a, respectively, are mounted on suitable shafts also journaled in the bearings 73. These gears also have clutch members for cooperating alternately with corresponding members on a shaft 81 which is similar in general to the shaft 76 in that it has movable bearings 82. The shaft 81 is provided with a sleeve 83 splined thereto, the opposite sides of which rotatably support upstanding bearing posts 84. A gear 85 is keyed to the 55 sleeve 83. A nest of gears 86 of slightly different sizes are secured to a shaft mounted in suitable bearings at the upper ends of the posts 84.

Bearing posts 87 and 88 are secured to the bottom of the casing 60. A differential gear 89 having a spur gear 90 formed integral therewith, is mounted on a suitable shaft carried in the bearing post 88. The gear 90 is in mesh with the gear 78 on the shaft 76. A differential shaft 91 is journaled in the bearings 87 and 88 and in a bearing 92 in the end wall of the casing. A differential gear 93 having a spur gear 94 integral therewith, is journaled on the shaft 91. The spur gear 94 is adapted to mesh with one of the gears of the nest 86. A differential pinion 95 is journaled in a spider 96 keyed to the shaft 91. The pinion 95 is in mesh with the gears 89 and 93.

With the parts in the positions shown in Figure 11, it will be apparent that the shaft 76 will 75

be driven at a speed proportional to that of the left hand cooling sheave shown in Figure 10. At the same time, the shaft 81 will be driven at a speed proportional to that of the right hand cooling drum. The drive for the shaft 76, of course, is effective through the engaged clutch members on the shaft and the gear 75. The drive for the shaft 81 includes the gears 75a and 80 and the clutch members on the gear 80 and the shaft 81 itself.

Assuming that the material is moving through the mill in the direction of the arrow shown in Figure 10, the shaft 81 will be driven at a speed proportional to that of the material issuing from the mill. The shaft 76 will be driven at a speed proportional to that of the material entering the mill. The differential gear 89 will be driven through the spur gears 78 and 90 at a speed proportional to that of the entering material.

The differential gear 93 will be driven by the spur gear and one of the gears of the nest 86 in mesh therewith at a speed proportional to that of the issuing material. Because of the interposition of the gear nest 86, the gears of which are smaller than the gear 94, the latter is driven at a speed which is equal to the speed of the gear 89 as long as a predetermined ratio exists between the speeds of the material entering and leaving the mill. This ratio is the same as that between the sizes of the active gear of the gear nest and the gear 94. By providing in the gear nest 86 a plurality of gears, the pitch diameters of which have the same ratios to the pitch diameter of the gear 94 as the gauge of the material leaving the mill to that of material entering the mill, for the various desired percentages of reduction, therefore, the differential gears will be driven at the same speed in opposite directions, of course, as long as the speed of the material leaving the mill bears a certain ratio to the speed of the material entering the mill, indicating that the selected percentage reduction in gauge (determined by which gear of the nest 86 is in mesh with the gear 94) is being effected.

As long as the gears 89 and 93 rotate at the same speeds in opposite directions, of course, the pinion 85 rotates, but the spider 96 and the shaft 91 are stationary. Any difference in the speeds of the differential gear, of course, will be reflected immediately by a corresponding rotation of the spider and differential shaft. An indicator disc 97 mounted on the outer end of the shaft 91, provides a readily visible showing of the difference in speeds. Markings may be applied to the peripheral face of the disc, or otherwise, to facilitate observation.

Means are provided for adjusting the position of the gear nest to set the indicator for different percentages of reduction, including a vertical shaft 98 having a fork 99 extending radially thereof. The left hand bearing post 84, as observed in Figures 11 and 12, is provided with a toothed projecting finger 100 adapted to cooperate with a plate 101 secured to the bearing post 87 and having a notched edge. The notches in the edges of the plate 101 are arranged in number and depth to permit the engagement of any one of the gears of the nest 86 with the gear 94. The gear nest as a whole is rotatable about the shaft 81, of course, and is normally urged toward the gear 94 by a spring 102 suitably secured at one end to the post 88 and attached to a pin 103 projecting inwardly of the right hand bearing post 84.

The shaft 98 is bored out to receive a push

rod 104. The push rod engages a lifting finger 105 pivoted in the fork 99 and extending through a slot in the shaft 98. The lifting finger 105 cooperates with a projection 106 extending from the toothed member 100. When the push rod 104 is depressed, the outer end of the finger 105 is raised and the gear nest and its bearing posts are then swung clockwise on the shaft 81 so that the gear nest is clear of the gear 94. The toothed member 100 is also cleared from the notched edge of the plate 101. Rotation of the shaft 98 by means of a knob 98a, for example, moves the gear nest, its bearing posts, and the sleeve 83 along the shaft 81.

When a selected gear of the nest 86 has been aligned with the gear 94, release of the push rod permits the spring 102 to swing the gear nest counterclockwise so that the selective gear thereof engages the gear 94. Simultaneously, the toothed member 100 engages the notched edge 20 of the plate 101 to lock the gear nest in adjusted position. A pointer 107 secured to the shaft 98 and cooperating with a scale on the cover of the casing 60 serves to indicate the proper positions of the gear nest for putting the several gears 25 thereof in mesh with the gear 94. It will be apparent that almost any thickness of hot rolled strip may be reduced to the desired finished gauge by a proper selection of the percentages of reduction for the several passes through the mill. For the convenience of the operator, the adjustments of the mill to reduce the various gauges of hot strip to the various finished gauges will appear on a chart which will be provided, indicating the adjustments necessary for all possible 35 cases.

It will be apparent that the differential shaft 91 of the apparatus shown in Figures 8 through 14 will operate in exactly the same manner as the shaft 39 of Figures 1 through 7, to actuate the screwdown control contacts. These contacts have been shown associated with the differential gear mechanism only in Figure 11, but a repetition of the description thereof is unnecessary, since the construction and the manner of operation are identical. As will be apparent from Figure 11, the cross bar 41 is attached to the end wall of the casing 60.

It will be apparent that the shaft 81 must always be driven by the cooling drum on the side of the mill from which the material issues. When the direction of travel of the material is reversed, therefore, the connection of the shafts 71 and 72 to the shafts 76 and 81 must be reversed. The reversing lever 62 cooperates with a crank 108. The crank is of U-shape and serves to actuate a pivot bar 109 resting on the floor of the casing 60 for angular movement about a central pivot. The bearings 77 and 82 for the shafts 76 and 81 are carried on slide rods 110 and 110a supported in bearings 111. When the crank 108 is in the position shown in Figure 11, the bearings of the shaft 76 are shifted to the left, and those of the shaft 81 to the right. The gear 75 is thus connected to the shaft 76 and the gear 80 to the shaft 81. Reverse movement of the crank 108, which is effected as previously described, by the operation of the main reversing lever 5, swings the pivot bar 109 in a clockwise direction, as shown in Figure 11, and causes the clutch members on the gear 75a and the shaft 76 to engage while the previously engaged clutch members on the shaft and the gear 75 are separated. At the same time, the gear 79 is connected to the shaft 81 by the engagement of the 75

clutch members and the shaft is made independent of the gear 30. Upon reverse travel of the material, the device will operate in the manner previously described to indicate variations from the selected rate of reduction.

It will be apparent from the foregoing description that the invention provides a highly efficient and satisfactory means for determining the departures of the rate of reduction from a selected value. The automatic screwdown control mechanism, furthermore, makes it unnecessary for the operator to concern himself with the adjustment of the rolls. If the strip comes through the mill too thick, the screwdowns will be properly adjusted and the selected rate of elongation will be maintained. Similar adjustment in the opposite direction is effected automatically if the material is too thin. The screwdown control itself is characterized by a quick response and by freedom from hunting. The rate of elongation may thus be maintained accurately within narrow limits at all times. The method and apparatus for measuring the rate of reduction of the material by comparing the speeds of the material entering and leaving the mill, are obviously a marked improvement over prior means for accomplishing similar results. The measuring apparatus disclosed is remarkably accurate and at the same time, is so simple in construction as to render its manufacture at a reasonable cost readily possible.

While I have illustrated and described herein only certain preferred embodiments of the invention, it will be apparent to those skilled in the art that numerous changes in the construction described may be made without departing from the spirit of the invention or the scope of the appended claims.

I claim:

1. The combination with a rolling mill having screwdowns, and a gauger operative on a change in the ratio of the entering and exit speeds of the material traversing the mill, of means controlled by the gauger for tightening and releasing the screwdowns.

2. The combination with a rolling mill having screwdowns, and means for comparing the speed of the material entering the mill with the speed of the material emerging from the mill, of means actuated by the speed comparing means for operating the screwdowns.

3. The combination with a rolling mill having screwdowns, and a differential gear mechanism for comparing the speed of the material entering the mill with the speed of the material emerging from the mill, of means controlled by said differential mechanism for controlling the operation of the screwdowns.

4. Apparatus for controlling the adjustment of rolling mill screwdowns comprising a shaft, differential gearing for rotating the shaft when the relation of the speed of material issuing from the mill to the speed of material entering the mill varies from a predetermined value, contacts operated by said shaft, and a screwdown motor controlled by said contacts.

5. Apparatus for controlling the screwdowns of a rolling mill comprising means responsive to a variation in the ratio of the speed of the material entering the mill to the speed of the material issuing from the mill, contact-operating means actuated by said first-mentioned means; a screwdown motor controlled by said contact-operating means, and means responsive to the energization of the screwdown motor for freeing

the contact-operating means from said first-mentioned means.

6. In a screwdown control for rolling mills, means responsive to the ratio of the thicknesses of material before and after passing through the mill including a shaft, a screwdown motor, contacts for controlling the screwdown motor, means actuated by the shaft and normally secured thereto for operating the contacts, and electromagnetic means for freeing the contact-operating means from said shaft.

7. A differential gauger for measuring the thickness of a strip while traversing a rolling mill, comprising differential gearing including two differential gears and a differential pinion 15 meshing therewith, means for driving one of said gears at a speed proportional to that of the material entering the mill, means for driving the other gear at a speed proportional to that of the material issuing from the mill, and an indicator 20 driven by movement of said pinion.

8. A differential gauger for measuring the thickness of material traversing the rolling mill comprising differential gearing including two differential gears and a differential pinion meshing therewith, means for driving said gears at speeds proportional to the entry and exit speed of the material, the drive for one of said gears including a speed change gear, and an indicator 25 shaft actuated by movement of said differential 30 pinion.

9. A differential gauger for measuring the thickness of material traversing the rolling mill comprising a shaft, means for driving the shaft at a speed proportional to that of the material 35 entering the mill, a second shaft, means for driving the second shaft at a speed proportional to the speed of material leaving the mill, the speed of the second shaft being different from that of the first, speed change gears on said second 40 shaft, differential gears driven by the first shaft and by one of the speed change gears on the second shaft, a differential pinion meshing with said differential gears and an indicator actuated on movement of said pinion.

10. A differential gauger for measuring the thickness of material traversing the rolling mill comprising a shaft, means for driving the shaft at a speed proportional to that of the material entering the mill, a second shaft, means for driving the second shaft at a speed proportional to that of the material leaving the mill, differential 50 gears driven by said shafts, a differential pinion meshing with said gears for actuating an indicator, and means for interchanging the connection between said shafts and their driving 55 means.

11. Apparatus for gauging the thickness of material traversing the rolling mill comprising differential gears, a differential pinion meshing with said gears, an indicator actuated by movement of said pinion, and means for driving said gears at speeds proportional to those of the material entering the mill and the material leaving the mill, the drive for one of said gears including a 60 speed change mechanism.

12. A gauger for strip mills comprising a differential gearing, means for driving one side of the gearing at a speed proportional to that of the material entering the mill, means for driving 70 the other side of the gearing at a speed proportional to that of material leaving the mill, and means for interchanging the drives of the respective sides of the differential gearing.

13. The apparatus defined by claim 12 wherein 75

- said interchanging means comprises a plurality of clutches between the driving means and the differential gearing, and means for engaging and disengaging said clutches in pairs.
5. 14. The apparatus defined by claim 12 wherein the drive for one side of the differential gearing includes a nest of gears differing slightly in diameter, said gears being selectively engageable with a gear on one side of the differential gearing.
10. 15. In combination with a rolling mill, means for measuring the effective surface speed of a work piece as it enters said mill and as it leaves said mill, and automatic means for actuating the screwdown of said mill in accordance with said measurement.
15. 16. In combination with a rolling mill, means for measuring the effective surface speed of a work piece as it enters and as it leaves said mill, means for causing the differential actuation of a member in accordance with said speeds, adjusting means permitting the selection of a desired speed ratio, and means actuated by said member to control the screwdown of said mill.
20. 17. In combination with a rolling mill having a motorized screwdown, means for measuring the effective surface speeds of a work piece as it enters and leaves said mill, means for causing said measurements to be subtractively effective to cause movement of a member, contacts associated with said member and an electric means associated with said contacts to energize the screwdown motor in accordance with the movements of said member.
25. 18. The combination with a rolling mill having screwdowns and a driving motor therefor, of means for comparing the entering and exit speeds of the material traversing the mill and controlling the screwdown motor, and means independent of said motor for stopping the motor after a fixed, predetermined, short interval.
30. 19. The combination with a rolling mill having screwdowns, a motor for adjusting the screw-
- downs, and means responsive to the ratio of entering and exit speeds of the material traversing the mill for automatically initiating operation of said motor, of means for stopping the motor after a fixed, predetermined, short interval of 5
35. 20. The combination with a rolling mill, a gauger having a reversible member operable in response to a comparison of the entering and exit speeds of material traversing the mill, screwdowns for the mill, a motor adapted to operate the screwdowns, and contacts controlling the operation of said screwdown motor operable by said reversible member.
40. 21. The apparatus defined by claim 20, characterized by contact-operating means releasably attached to said reversible member, and means for freeing the contact-operating means from the reversible member within a predetermined, fixed time after operation of one of said contacts.
45. 22. The apparatus defined by claim 20, characterized by contact-operating means connected to said reversible member by a friction clutch, an electromagnet effective for disengaging said friction clutch, and means controlled by said aforementioned contacts for energizing said electromagnets.
50. 23. The combination with a rolling mill, of means for comparing the linear speeds at which a work piece enters said mill and leaves said mill, and automatic means for actuating the screwdown of said mill in accordance with said comparison.
55. 24. The combination with a rolling mill, of screwdowns for controlling the thickness of the material issuing from the mill, means for comparing the speeds of the material entering and leaving the mill, means controlled by said means for adjusting the screwdowns, and means for arresting said screwdown operating means after a predetermined time subsequent to the commencement of its operation.

HOWARD S. LAMB.
